UNITED STATES PATENT OFFICE.

CHRISTIAN HIERING AND ALBERT FULLER, OF NEWARK, NEW JERSEY.

DESIGN FOR A BAG-FASTENING MEMBER.

No. 39,218.

Specification for Design.

Patented March 24, 1908.

Application filed June 19, 1907. Serial No. 379,819. Term of patent 7 years.

To all whom it may concern:

Be it known that we, CHRISTIAN HIERING and ALBERT FULLER, citizens of the United States, residing in the city of Newark, in the county of Essex and State of New Jersey, have invented a new, original, and ornamental Design for a Bag-Fastening Member, of which the following is a specification, reference being had to the accompanying drawings, forming a part thereof.

Figure 1 is a side elevation of a bag fasten-

ing member embodying our new design, and Fig. 2 is a plan view of the same.

We claim:

The new and ornamental design for a bag fastening member, as shown.

CHRISTIAN HIERING.
ALBERT FULLER.
